UNITED STATES PATENT OFFICE.

ROBERT WHITTON, OF NORTHAMPTON, ENGLAND.

WINDOW-FRAME.

SPECIFICATION forming part of Letters Patent No. 681,467, dated August 27, 1901.

Application filed January 2, 1901. Serial No. 41,865. (No model.)

To all whom it may concern:

Be it known that I, ROBERT WHITTON, a subject of the Queen of Great Britain, residing at Castilian Works, 24 and 26 St. Giles street, Northampton, England, have invented new and useful Improvements in Window-Frames, of which the following is a specification.

This invention relates to improvements in window-frames, and has for its object to provide an improved construction of frame the sashes of which are pivoted in such a manner that they can be turned upon the pivots for purposes of cleaning.

According to the invention instead of mounting the sashes in grooves in the frame of the window I form the said sashes with lateral grooves adapted to take upon guide-rods. These guide-rods are pivoted to the frame and extend from the bottom of the frame in the case of the bottom sash to, say, about the middle of the frame and in the case of the upper sash from the upper end of the frame to, say, about the middle thereof.

In lieu of the usual weights and cords I employ springs of any suitable construction, which fit between the lateral grooves in the sashes and the guide-rods upon which they run, the said springs being of sufficient strength to retain the window in any position to which it may be moved.

To retain the sashes firmly in the closed position, I advantageously divide the guide-bars at the upper end in the case of the upper sash and at the lower end in the case of the lower sash, the end portions being rigidly fixed to the sash or frame. In this case it is necessary to raise or lower the sash so as to disengage the fixed portion of the guide-bar from the groove in the sash before the latter can be turned upon the pivots. Furthermore, short fixed lengths of guide-bar are advantageously provided at the upper and lower ends of the frame to engage the grooves in the lower and upper sashes, respectively, when they are opened.

In the accompanying drawings, Figure 1 is a sectional elevation of a window constructed according to the invention and showing the architraves removed. Fig. 2 is a vertical section on the line 2 2, Fig. 1. Fig. 3 is a view similar to Fig. 2, but showing the sashes of

the window removed. Fig. 4 is a view also similar to Fig. 2, but showing the sashes opened and turned upon their pivots. Fig. 5 is a section on the line 5 5 of Fig. 1, and Fig. 6 is a view showing an improved form of fastening. Figs. 5 and 6 are drawn to a larger scale than Figs. 1 to 4.

a is the window-frame, and *b b* the sashes 60 thereof.

c c are the lateral grooves formed in the sashes, and *d d e e* are the guide-rods with which the said lateral grooves engage. The guide-rods *d d* extend from the bottom of the window-frame upward to about the middle thereof, and the guide-rods *e e* extend from the top of the frame downward to about the middle of the said frame, both sets of guide-rods being pivoted, as shown at *d* and *e*, respectively, to the frame *a* and divided near the bottom and top, respectively, so as to leave portions *f* and *g*, which are permanently fixed to the frame *a*, so that the sashes when closed are firmly retained in position.

h h are the short lengths of guide-bar, which are fixed to the frame at the upper and lower ends thereof opposite or in alinement with the lower and upper guide-rods, respectively, the object of these fixed lengths of bar 80 being to engage the grooves in the lower and upper sashes, respectively, when they are fully opened, so as to retain them in their open position.

i i are the springs, which are fitted between 85 the lateral grooves *c* in the sashes *b b* and the guide-rods *d* and *e*, upon which they run, the said springs being of sufficient strength to retain the window in any position to which it may be moved. With this construction when 90 it is desired to clean the outside of the window, for example, from the inside of a room the sashes can be swung upon the pivots *d* and *e* of the guide-rods *d* or *e*, which turn with them; but before this can be done the 95 sashes must be moved until they are free of the fixed portions of the guide-rods. The arrows in the drawings indicate the direction in which the sashes are turned upon the guide-bar pivots.

My improved construction of window-frame has the further advantage that where it is desired to reglaze a broken window, for example, the whole sash *b* can be slid off the guides

d and *e*, as indicated by the broken lines in Fig. 4, and sent away for repair.

In the drawings I have shown architraves *a'* attached to the frame *a* and projecting 5 slightly beyond the inner edge of the said frame. As, therefore, those at the sides will be in the way when it is desired to turn the sashes on their pivots, I arrange so that they can be moved out of the way, and to this end 10 I advantageously provide them with screws *a²*, the heads of which engage slots *a³* in the frame *a*, as shown clearly in Fig. 5.

Fig. 6 shows an improved fastener which I advantageously employ in conjunction with 15 my improved window. It comprises a slotted catch *j*, fitted in a recess in the meeting-rail of the upper sash, and a pin *k*, which extends transversely through the meeting-rail of the lower sash and is formed at its inner 20 end with a flat head *k'* and at its outer end, which projects beyond the front face of the meeting-rail, with a knob *k²*, by means of which the head *k'* can be turned so that it can be passed through the slot in the catch *j* 25 and turned at right angles, so as to hold the two rails together, as clearly shown in the figure.

l is a spring which is coiled around the pin *k* and abuts at one end against a stop *m*, fixed 30 in the lower meeting-rail, and at the other end against a stop or shoulder *n* upon the pin *k*. This spring normally holds the pin *k* in its outermost position or out of engagement with the slotted catch *j*.

35 Having now particularly described and ascertained the nature of my said invention and in what manner the same is to be performed, I declare that what I claim is—

1. The combination with the window-frame, 40 of guide-bars for the upper sash extending from points adjacent to the top of the frame downward adjacent to the center, and pivoted to said frame substantially centrally of their length, a pair of guide-bars for the lower 45 sash extending from points adjacent to the bottom of the frame upward adjacent to the center, and pivoted substantially centrally of their length to said frame, at points below the pivots of the upper-sash guides, and upper 50 and lower sashes adapted to engage said guides, whereby said sashes can be moved up and down on said guides and can be independently swung on the pivots of said guides, substantially as described.

55 2. The combination with the window-frame, of guide-bars for the upper sash extending from points adjacent to the top of the frame downward adjacent to the center, and pivoted to said frame substantially centrally of 60 their length, a pair of guide-bars for the lower sash extending from points adjacent to the bottom of the frame upward adjacent to the center, and pivoted substantially centrally of their length to said frame, at points below 65 the pivots of the upper-sash guides, and upper and lower sashes adapted to engage said guides, whereby said sashes can be moved up

and down on said guides and can be independently swung on the pivots of said guides, 70 said guide-bars and sashes being provided the one with retaining devices engaging the other to hold said sashes at any desired positions on said guide-bars, substantially as described.

3. The combination with a window-frame, 75 of guide-bars for one sash extending from points adjacent to the top downward adjacent to the center and guide-bars for the other sash extending from points adjacent to the bottom upward adjacent to the center, said guide-bars being pivoted to said frame, stationary 80 guide-bars in line with each of said pivoted guide-bars and sashes adapted to engage and slide on said guide-bars, substantially as described.

4. The combination with the window-frame, 85 of guide-bars for the upper sash extending from points adjacent to the top of the frame downward adjacent to the center, and pivoted to said frame substantially centrally of their 90 length, a pair of guide-bars for the lower sash extending from points adjacent to the bottom of the frame upward adjacent to the center, and pivoted substantially centrally of their length, to said frame, at points below the pivots 95 of the upper-sash guides, and upper and lower sashes adapted to engage said guides, whereby said sashes can be moved up and down on said guides and can be independently swung on the pivots of said guides, and stationary 100 guide-bars arranged at the top and also at the bottom of said frame in line with the upper and lower sash guides, substantially as described.

5. The combination with the window-frame, 105 of guide-bars for the upper sash extending from points adjacent to the top of the frame downward adjacent to the center, and pivoted to said frame substantially centrally of their length, a pair of guide-bars for the lower sash 110 extending from points adjacent to the bottom of the frame upward adjacent to the center, and pivoted substantially centrally of their length to said frame at points below the pivots 115 of the upper-sash guides, and upper and lower sashes adapted to engage said guides, whereby said sashes can be moved up and down on said guides and can be independently swung on the pivots of said guides, stationary guide-bars arranged at the top and bottom of said 120 frame in line with the upper and lower sash guides, and springs secured to each of said sashes and engaging the guides therefor, to hold the sash in any desired position on said guides, substantially as described.

6. The combination with the window-frame, 125 of guide-bars for the upper sash extending from points adjacent to the top of the frame downward adjacent to the center, and pivoted to said frame substantially centrally of their 130 length, a pair of guide-bars for the lower sash extending from points adjacent to the bottom of the frame upward adjacent to the center, and pivoted substantially centrally of their

length, to said frame, at points below the pivots of the upper-sash guides, and upper and lower sashes adapted to engage said guides, whereby said sashes can be moved up and down on said guides and can be independently swung on the pivots of said guides, and a locking device for securing the meeting-

rails of the upper and lower sashes together to prevent either a swinging or sliding movement of the same, substantially as described.
